EDUARD GELBKE, OF JERSEY CITY, NEW JERSEY, ASSIGNOR OF ONE-HALF TO
ALEXANDER SCHEFFLING, OF JERSEY CITY, NEW JERSEY.

WINDOW.

984,271.

Specification of Letters Patent. Patented Feb. 14, 1911.

Application filed December 1, 1910. Serial No. 595,057.

To all whom it may concern:

Be it known that I, EDUARD GELBKE, a citizen of the United States, residing at Jersey City, county of Hudson, and State 5 of New Jersey, have invented a new and Improved Window, of which the following is a specification.

This invention relates to a window having combined sliding and folding sashes. The 10 construction is such that when the sashes are swung open upon their hinges, they are locked against vertical displacement, while when they are closed, they may be freely slid up or down within the window frame. 15 In the accompanying drawing: Figure 1 is a front elevation of a window embodying my invention; Fig. 2 a horizontal section through the window showing both sashes lowered, and Fig. 3 a vertical section through 20 one of the jambs.

To each jamb 10 of a window frame 11, is secured a rack 12 having downwardly pointing teeth. Each of the racks is encompassed by a hollow rail 13 having a 25 rear slit 14 for accommodating the rack. The rail is freely slidable along the jamb, to which it is held by rack 12 and is provided at its inner side with a longitudinal slot 15. Back of this slot, there is pivoted 30 to the rail at 16 a pawl 17 adapted to engage rack 12 with its upper end. To this upper end there is connected the sash cord 18, passing over the usual pulley 19, and connected at its lower end to the sash weight 35 20. This weight has a tendency to swing the upper end of the pawl into engagement with the rack, and to project the lower end of the pawl out of rail 13 through slot 15 (Fig. 3). To one of the rails 13 is hinged 40 at 21, one stile of a sash 22 which with its other beveled stile is adapted to engage the other correspondingly beveled rail 13, and to be secured thereto by catch 23. Tongues 24 on rails 13, adapted to be received by 45 corresponding slots 25 of sash 22 serve to interlock the closed sash with the rails and thus take the strain off hinges 21 and catch 23. When the sash is closed, it will bear 50 against the lower protruding ends of pawls 17, so that the latter are retracted and their

upper ends are caused to release rack 12. The rails together with the sash may now be freely moved up or down within the window frame, like any other balanced sliding sash. When however the sash is opened, its 55 stiles will recede from latches 17, so that the latter will under the influence of weights 20 be thrown into engagement with racks 12. In this way, both rails 13, as well as the sash are locked against vertical displacement. 60

It will be seen that with my construction, the sashes may be freely slid up or down, or swung upon their hinges, and that when opened they are automatically locked against 65 vertical displacement. If the window is to be washed, both sashes may be lowered and opened as shown in Fig. 2, so that both sides of each sash are freely accessible.

I claim:

1. A window provided with racks extending along the window frame, rails movable along the said frame, weight-controlled pawls pivoted to the rails and adapted to engage the racks, and a sash hinged to one 75 of the rails and adapted to engage the other rail, said sash being in engagement with the pawls when in its closed position, and out of such engagement in its open position.

2. A window provided with racks extending along the window frame, slotted hollow rails encompassing said racks, weight-controlled pawls pivoted to the rails and adapted to engage the racks, and a sash hinged to one of the rails and adapted to engage the 85 other rail, said sash being in engagement with the pawls in its closed position and out of such engagement in its open position.

3. A window provided with racks extending along the window frame, slotted hollow 90 rails encompassing said racks, weight-controlled pawls pivoted to the rails and adapted to engage the racks, a sash hinged to one of the rails and adapted to engage the pawls, and means for interlocking the sash with the 95 rails.

EDUARD GELBKE.
